UNITED STATES PATENT OFFICE.

HERBERT CORRAL, OF HELENSBURGH, AND JAMES HEGGIE, OF CLYDEBANK, SCOTLAND, ASSIGNORS TO THE SINGER MANUFACTURING COMPANY, OF ELIZABETH, NEW JERSEY, A CORPORATION OF NEW JERSEY.

THREAD-DRAWING MACHINE.

Application filed August 26, 1926, Serial No. 131,602, and in Great Britain September 22, 1925.

This invention relates to improvements in machines for drawing threads in fabrics to be hemstitched.

A machine for this purpose comprises a frame which may be constructed as a sewing machine frame fitted with operatively connected upper and lower rotary shafts, fabric-feeding mechanism including a feed-dog, a presser-bar with presser-feet, a vertically reciprocating piercer-bar carrying a spear-like piercer with a serrated edge, adapted to penetrate slots in the presser-feet and in the throat-plate transverse to the line of the feed, and a rotary cutter carried by the lower rotary shaft and having a cutting edge disposed transversely of the direction of feed.

In accordance with the invention there is mounted for vertical reciprocation in the head of the arm of the frame, intermediate the piercer-bar and the presser-bar, a bar carrying a pair of flat fabric-depressing fingers with rounded lower edges, one on each side of the piercer, in line with the pivots of the presser-feet, these fingers being adapted to penetrate slots in the presser-feet and to enter slots in the throat-plate extending in the direction of feed.

This intermediate bar may be conveniently operated from a rock-shaft mounted in the head and deriving its actuation from an eccentric on the upper shaft, said rock-shaft having an arm disengagably connectible with the intermediate bar, the arrangement being such that in their descent the fingers engage the fabric at about the same time as the piercer, and, travelling a less distance, depress the fabric in the slots in the throat-plate, reaching the lower limit of their stroke at about the same time as the piercer, and releasing the fabric in their ascent to permit the feeding movement following the withdrawal of the piercer.

The action of the fingers is thus to stretch laterally the fabric clamped between the presser-foot and the throat-plate.

The fabric having been stretched and pierced and the threads drawn beneath the throat-plate having been severed by the cutter, the fabric is fed a step into position for a fresh piercing and severing operation.

As is understood, in the continued operation of the machine, the piercer makes a line of spaced penetrations in the fabric, the serrated edge pushing the threads to be drawn

beneath the throat-plate, and these threads 55 being thereupon severed.

The invention is illustrated in the accompanying drawings in which Fig. 1 is an end elevation of the head of the upper arm with the usual cover-plate removed, showing also the rotary cutter and feed-actuating mechanism. Fig. 2 is a front side elevation, part vertical section showing the operating parts adjacent to the head. Figs. 3 and 4 are detail views of connections for operating the 60 finger-carrying bar. Figs. 5 and 6 are detail views of the fabric depressing fingers. Fig. 7 is a plan of the throat-plate, below which is the feed-dog. Fig. 8 is a plan of the 65 feed-dog. Fig. 9 is a view of the lower end 70 of the presser-bar with presser-feet, the latter being tilted to show the slots therein. Fig. 10 is a part side elevation part section through the machine frame showing the connections 75 between the upper driving shaft and the lower shafts. Fig. 11 is an inverted plan of the complete machine. Fig. 12 is a transverse vertical section in the plane of the piercer-bar and Fig. 13 is a section on the line 13—13, Fig. 3.

The machine illustrated comprises a frame constructed as a sewing machine frame with an upper rotary driving shaft 1 operatively connected to a lower rotary shaft 2 and to a feed rock-shaft 3 and a feed-lift rock-shaft 4. 85 Mounted in the head 5 of the arm 6 of the frame is a presser-bar 7 urged downwardly by a spring 8 and carrying twin presser-feet 9, 10, in parallel adapted to tilt on horizontal axes transverse to the lines of feed, the shanks 90 of said presser-feet being connected for reciprocal vertical movements by a balance member 10' journaled on a block 10² at the lower end of the presser-bar 7. The upper 95 rotary shaft 1 is connected by a crank 11 and link 12 with a vertically reciprocating bar 13 located in front of the presser-bar 7 as seen by the operator. Clamped to the lower end 100 of the bar 13 by a screw 14 is a spear-like piercer 15 having a serrated edge and adapted to penetrate registering slots 16 in the presser-feet 9, 10, and a slot 17 in the throat-plate 18 transverse to the line of the feed. The lower rotary shaft 2 carries a rotary cutter-blade 19 having a cutting edge disposed transversely 105 of the direction of feed and cooperative with an edge 20 on the under side of the throat-plate 18.

Mounted for vertical reciprocation in the head, intermediate the piercer-bar 13 and the presser-bar 7 is a bar 21 carrying a pair of flat fabric-depressing fingers 22 with rounded lower edges, one on each side of the piercer 15, in the line joining the pivots 23 of the presser-feet, these fingers 22 being adapted to penetrate slots 24 in the presser-feet and to enter slots 25 in the throat-plate 18 parallel with the feed-slots therein.

The bar 21 is disengageably connected by an arm 27 with a rock-shaft 28 mounted in the head 5 and deriving its actuation through a bifurcated arm 28' from an eccentric 29 on the upper shaft 1, the arrangement being such that in their descent the fingers 22 may engage the fabric at about the same time as the piercer 15, and, travelling a less distance, depress the fabric in the slots 25 in the throat-plate 18, reaching the lower limit of their stroke at about the same time as the piercer 15, and releasing the fabric in their ascent to permit the feeding movement following the withdrawal of the piercer.

The action of the fingers 22 is thus to stretch laterally the fabric clamped between the presser-feet 9, 10 and the throat-plate 18 and to be acted on by the piercer 15 and fed by the feed-dog 30.

The feed-dog 30 presents parallel series of serrations, comprising two outer series 31, 32, one outside of each finger 22, adapted to project through elongated feed-slots 33 in the throat-plate 18, each extending from a point in front to a point behind the path of the piercer 15, and two short series of serrations 34, 35 located between the fingers 22 and adapted to project through intermediate

feed-slots 36 in the throat-plate 18 extending rearwardly from points behind the path of 40 the piercer.

As is understood, in the continued operation of the machine, the piercer 15 makes a line of spaced penetrations in the fabric, the serrated edge pushing the threads to be 45 drawn beneath the throat-plate 18 for severance by the cutter 19 in rotation of the lower shaft 2.

Having thus set forth the nature of the invention, what we claim herein is:— 50

1. A thread-drawing machine having a throat-plate, a presser-bar and a vertically reciprocatory piercer-bar above the throat-plate, a piercer carried by said piercer-bar, vertically movable fabric-depressing fingers, 55 one on each side of said piercer, presser-means carried by said presser-bar and formed with slots for said piercer and fabric-depressing fingers, said throat-plate also having slots for said piercer and fingers, a feeding device and rotary cutter below the throat-plate, and means for reciprocating said fingers to project them through the slots in the presser-means and into the slots in the throat-plate. 60

2. The combination set forth in claim 1 in which the finger actuating mechanism is timed to move the fingers into engagement with the work concomitantly with the piercer, and thereafter to move the fingers a 70 lesser distance than the piercer is moved.

In testimony whereof, we have signed our names to this specification.

HERBERT CORRALL.
JAMES HEGGIE.
